UNITED STATES PATENT OFFICE.

JAMES H. RAND, OF NORTH TONAWANDA, NEW YORK, ASSIGNOR TO RAND KARDEX BUREAU, INC., OF TONAWANDA, NEW YORK, A CORPORATION OF DELAWARE.

INDEX DEVICE.

Application filed December 26, 1923. Serial No. 682,647.

This invention relates to a rotary index of the so-called "visible index" type wherein the index elements are supported to turn about a common axis, and consists in the 5 novel and improved features of construction hereinafter described and particularly pointed out in the claims.

In the accompanying drawings which illustrate a preferred form of the invention.

Fig. 1 is a fragmentary end elevation of a desk such for example as that used by telephone operators, having an index constructed in accordance with the present invention mounted thereon;

Fig. 2 is a front elevation of the index device;

Fig. 3 is a fragmentary sectional view of a portion of the index device to larger scale showing details of the means employed for 20 supporting the movable leaves of the index;

Fig. 4 is a horizontal section on the line 4-4 of Fig. 3;

Fig. 5 is a vertical section on the line 5-5 of Fig. 3; and

Fig. 6 is a fragmentary rear view of the 25 movable leaf shown in Fig. 3.

Referring to the drawings, the numeral 1 indicates the central part of a desk having working tables 2-2 at its opposite sides at 30 which operators may be conveniently stationed.

A frame or stand 3 is mounted upon the central part of the desk, constituting supporting means for the movable portions of 35 the index. This frame may be devised to support one or more units of the index, two such units being illustrated in the present drawings.

At the upper part of the frame a horizontal shaft 4 is mounted and on this shaft 40 pairs of discs 5-6, 7-8, are arranged to turn, the number of pairs of discs corresponding to the number of index units employed. Preferably the shaft 4 is fixedly 45 secured in the frame and the discs are mounted to rotate thereon. Each of the discs is provided with a series of circumferentially spaced openings, the openings of each disc being disposed opposite to and in 50 alignment with the openings of the associated disc of a pair.

Referring more particularly to Figs. 3, 4 and 5, the discs 5 and 6 are shown as connected by rods or pins 7. Preferably the 55 openings in one of the discs, as for example

the disc 5, are internally threaded for engagement with the threaded ends of the supporting rods or pins 7, while the openings in the disc 6 are recessed for the reception of the enlarged heads 9 of the rods or pins 60 7. These heads may be slotted if desired for the reception of a screw driver blade, forming a convenient means for removably assembling the pins or rods with the discs.

The rods or pins 7 constitute pivotal supports for the movable index holders 10. As a convenient mode of attaching the index holders to the pins, the holders may be provided with integral sleeve-like portions 11 65 at their upper ends which receive the pins 70 or rods 7 and which, together with such rods, constitute hinges permitting the free swinging of the index holders between the corresponding pair of discs. Other modes of hingedly supporting the holder between 75 the discs are contemplated as within the spirit of the present invention.

Each holder 10 is preferably formed from transparent sheet material such, for example, as celluloid, having its opposite lateral edges folded to provide the overlapping flanges 12, 13, respectively. Preferably the edges of these flanges are bent on themselves to provide a smooth finish. By reason of the resiliency of the material of which the 80 holder is formed the flanges securely and firmly engage the ends of index slips 14 which are positioned within the channels formed by the flanges. While such flanged 85 holders are preferred for the purpose, it is contemplated that transparent envelopes may be substituted therefor if desired.

The index slips may bear suitable indicia as, for example, names, addresses, and telephone numbers of subscribers to a telephone 90 system. In accordance with the present invention it is contemplated that each of the index slips will be provided with identical 95 indicia upon opposite sides and as the material of the holder is transparent such indicia may readily be read from either side of the holder. The indicia may have the same side up on both sides of the slip, or reversed if desired, in accordance with the purpose and mode of use of the index.

While of utility in many situations where it is desired to have a large amount of informative data readily available to several persons, the present invention is of especial value for use in telephone exchange work,

where certain operators must have readily available a complete list of all the subscribers to the exchange together with their street addresses and telephone numbers. An index 5 of the type hereinabove described may readily be made to contain upwards of 300,000 names and addresses without occupying in excess of the 30 inch space allowed between adjacent operators on the same side of the desk. As the holders are arranged to 10 revolve about the axis of the shaft 4, each operator is able quickly to bring the proper holder into convenient position for reading and as the data carried by each holder is 15 readable from either side thereof the operator positioned at either side of the desk may obtain information from the index with the same facility. If the index were intended to be read from one side only it is 20 manifest that both sides of each holder might be made available by providing the slips with proper data on opposite sides, that on one side being upside down as compared with that on the other.

25 In the accompanying drawings no substantial attempt has been made at accuracy in proportion of parts as it is contemplated that the device may be constructed of any suitable size with such variations in detail 30 as may be found most desirable in accordance with the particular circumstances of its location and environment.

I claim:

35 1. An index comprising a support mounted to revolve freely in opposite directions, a stiff resilient holder carried by the support, the holder having integral flanges at its opposite edges, and a plurality of removable index slips provided with indicia upon their 40 opposite sides and having their ends secured beneath the respective flanges, the holder

being so constructed and arranged that the opposite sides of each slip are exposed to view.

2. An index comprising a frame, a shaft 45 mounted thereon, a pair of spaced discs carried by the shaft, a plurality of holders journaled between the discs, each holder comprising an integral piece of sheet celluloid having sleeve-like bearings at its upper end, 50 and having its lateral margins turned inwardly to provide for removably retaining one or more index holders.

3. An index comprising a frame, and a 55 series of transparent holders mounted in the frame to revolve in either direction about a common axis, each holder being constructed of transparent sheet material and having spaced flanges extending substantially at right angles to the axis of revolution, said flanges being constructed and arranged to grip index slips whereby the indicia on both sides of the index slips may be exposed to view, said slips being removable at will from said holder. 60

4. An index comprising a frame, a pair 65 of rotary, coaxially spaced discs mounted therein, said discs having circumferentially spaced openings therein, the openings of one disc aligning with those of the other to form 70 cooperating pairs, supporting means engaging each pair of openings, and a transparent holder carried by the supporting means which engages each pair of openings, said 75 holders being formed from sheet celluloid and having their marginal portions bent over to form flanges for removably retaining index slips.

Signed by me at Boston, Massachusetts, this 18th day of December, 1923.

JAMES H. RAND.
